UNITED STATES PATENT OFFICE.

EDWARD W. WUNCH, OF BUFFALO, NEW YORK.

TRANSFER-SLIP.

946,650.

Specification of Letters Patent. Patented Jan. 18, 1910.

Application filed May 3, 1909. Serial No. 493,615.

To all whom it may concern:

Be it known that I, EDWARD W. WUNCH, a citizen of the United States, residing at Buffalo, in the county of Erie and State 5 of New York, have invented certain new and useful Improvements in Transfer-Slips; and I do declare the following to be a full, clear, and exact description of the invention, such as will enable others skilled in 10 the art to which it appertains to make and use the same.

This invention relates to a transfer slip, such as is used in connection with street-railway systems and has for its object to 15 provide a transfer slip which may be used for as many transfers of the passenger as he or she may be entitled to, and may require.

With the foregoing and other objects in 20 view, the invention consists of certain novel features of construction, combination and arrangement of parts, as will be more fully described and particularly pointed out in the appended claim.

25 In the accompanying drawings: Figure 1 is a plan view of a transfer slip embodying my improvements, and Fig. 2 is a similar view showing another form of making the slip.

30 Referring to the drawings for a more particular description of the invention, 1, indicates one side of the slip, upon which is printed in the spaces, 2, the names of the respective stations. 3 indicates the other 35 side of the slip upon which is printed a time-table.

In carrying out the invention the side, 3, of the transfer-slip is spaced from the side portion, 1, leaving a vertical or longitudinal space 4, between the same which is 40 marked off by the lines, 5, into a number of spaces to correspond with the names of the stations printed upon the side portion, 1, of the slip.

45 In using a slip such as I have shown, should the passenger board a car and ask for a Broadway transfer the transfer is given him and punched in the space in which is printed "Broadway." If while on the 50 Broadway car the passenger desires a transfer for a Fillmore car the transfer is punched in the space, 4, at a point directly opposite the word "Broadway," and also punches opposite "Fillmore" indicating 55 that the transfer is canceled or void so far

as Broadway is concerned and is good on the Fillmore line. Upon boarding a Fillmore car the passenger asks for a transfer on the Main street line the conductor punches the space, 4, at a point directly opposite the word "Fillmore" and punches the space in which the word "Main," is printed thus indicating that the transfer is void so far as the Fillmore line is concerned but is good for a ride upon the Main street line. 60 Should the passenger ask for a transfer for the Hertel line the above operation is repeated. In this manner the passenger can go from one line to another at the permissible transfer points, but should he attempt 70 to make a circuit of the line or return to the starting point on the original fare paid the transfer slip showing the several stations punched by the conductor, will show that the passenger is not entitled to another 75 transfer. Thus the passenger cannot make a round trip or circuit on one ticket and the car company is thus protected.

Should the company decide that a passenger is entitled to a limited number of transfers the transfer slip will enable the conductor to readily see or ascertain when a passenger has had the number of transfers to which he is entitled by the company. The successive transfer slip also furnishes a complete record of the journey of the passenger and gives a very desirable record in case of a controversy with the passenger. 80

The blank space, 6, at the bottom of the transfer slip is to be punched by the conductor who takes up the transfers. It is to be further observed that by using a transfer slip such as I have shown and described, one slip is all that is necessary where three or four slips are ordinarily used, which will 95 amount to no inconsiderable sum where millions of these slips are used yearly.

From the foregoing it is thought that the advantages of my transfer system will be readily understood without requiring a more 100 extended explanation.

What I claim is:

A transfer slip having the names of the respective transfer stations printed on one side of its face in a vertical row or column, 105 and a time table on the opposite side thereof with its side portions spaced apart to provide a longitudinal space therebetween, said space being subdivided by transverse lines into a number of spaces alining with the re- 110

spective transfer stations, said slip also having the names of the respective months in the year printed in a horizontal row at the bottom, leaving a horizontal cancellation
5 space between the names of the months and the bottom of the time table and column of transfer stations.

In testimony whereof I have hereunto set my hand in presence of two subscribing witnesses.

EDWARD W. WUNCH.
